UNITED STATES PATENT OFFICE

139,894

DESIGN FOR A LIQUOR BAR

Harry J. Roberts and Rose Roberts,
University Heights, Ohio

Application June 10, 1944, Serial No. 113,951

Term of patent 14 years

(Cl. D80—2)

To all whom it may concern:

Be it known that we, Harry J. Roberts and Rose Roberts, citizens of the United States, residing in the city of University Heights, county of Cuyahoga, and State of Ohio, have invented a new, original, and ornamental Design for a Liquor Bar, of which the following is a specification, reference being had to the accompanying drawing, forming a part thereof.

We claim:
The ornamental design for a liquor bar, substantially as shown.

HARRY J. ROBERTS.
ROSE ROBERTS.
